UNITED STATES PATENT OFFICE.

EDWARD T. B. MURPHY, OF EAST HAVEN, CONNECTICUT.

GAME.

SPECIFICATION forming part of Letters Patent No. 644,209, dated February 27, 1900.

Application filed October 2, 1899. Serial No. 732,294. (No model.)

To all whom it may concern:

Be it known that I, EDWARD T. B. MURPHY, a citizen of the United States, residing at East Haven, county of New Haven, and 5 State of Connecticut, have invented a certain Improvement in Games, of which the following is a specification.

My invention is for a new and amusing game which I prefer to call "Can you capture the Filipinos;" and it consists of a suitable box having a spring-balanced table or surface with depressions formed therein for the reception of balls, and holes also formed therein for the reception of images of soldiers.

In order that those skilled in the art to which this invention appertains may understand how to make and use the same, the construction and operation will now be described 20 in detail, referring to the accompanying drawings, forming a part of this specification, in which—

Figure 1 is a perspective of a game-box made in accordance with my improvement; 25 Fig. 2, a section thereof, showing the means of balancing the table and showing the soldiers in position; and Fig. 3, an enlarged view of one of the soldier images.

In carrying out my invention as here embodied, A represents a rectangular box, which may be made of pasteboard or other suitable material and having its top open, as indicated at B. A table C is supported by the spring D, so as to be normally balanced when 35 the box is held in horizontal position, and the spring should be of such a tension as to cause the table to easily tip in any direction should a slight inequality of weight be placed upon any portion of its surface other than the exact center. The table has a series of depressions E formed in its upper surface for the reception and retention of the balls F, here shown as five in number, one being placed at the center. The table also has formed 40 45 therein the holes G for the insertion of the pegs H, one of which projects downward from the base I of each of the images J, so that

when these images are to be placed into position the pegs are placed within the holes, which will prevent the images from falling 50 from the table.

The object of the game is to place the five balls in position while holding the game-box in one hand, and then one by one place the images upon the table without causing the 55 balls to roll from the depressions, and, as is obvious, this will require nearly an equal amount of skill and patience for accomplishment, thus training the eye and steadyng the nerve, and thereby benefiting the manipulator.

My improved game will afford endless amusement for both young and old and will serve as an educational device.

The cost of manufacture of such a game is 65 comparatively small and may be made exceedingly attractive by being properly colored, figured, or printed.

Having thus fully described my invention, what I claim is—

1. A game consisting of a rectangular box having an open top, a spring secured to the bottom of the box, a table supported in a horizontal position on the upper end of the spring, said table having depressions for the 75 reception of balls and apertures by which figures are held against accidental displacement, substantially as described.

2. As a new article of manufacture, a game consisting of a rectangular box having an open 80 top, a spring secured within the box, a table mounted upon the spring, a series of balls adapted to be placed in depressions formed upon the table, and a series of images also adapted to be secured upon the table, as 85 specified.

In testimony whereof I have hereunto affixed my signature in the presence of two subscribing witnesses.

EDWARD T. B. MURPHY.
